UNITED STATES PATENT OFFICE

2,484,837

LIGHT SIGNALING MEANS

Burton G. Lake, Chula Vista, Calif.

Application June 27, 1938, Serial No. 216,182

1 Claim. (Cl. 250—1)

(Granted under the act of March 3, 1883, as
amended April 30, 1928; 370 O. G. 757)

1

My invention relates to a light signalling means wherein there is light radiation outside the visible spectrum, and particularly to infra-red radiation so that the light is invisible, and the objects of my invention are:

First, to provide novel means producing powerful and short flashes of radiant energy in the infra-red spectrum;

Second, to provide a means of this class by the use of which extremely powerful and short flashes of light are produced and transmitted at the will of the operator;

Third, to provide a means of this class in which a light absorbing filter is used for rendering invisible the light that is used; and

Fourth, to provide a means of this class which is very simple and economical of construction, easy to operate, very efficient in its action and which will not readily deteriorate or get out of order.

With these and other objects in view as will appear hereinafter, my invention consists of the certain novel features of construction, combination and arrangement of parts and portions as will be hereinafter described in detail and particularly set forth in the appended claim, reference being had to the accompanying drawings and to the characters of reference thereon which form a part of this application in which:

Figure 1 is a perspective view of a casing showing my cylindrical parabolic reflector with the gas discharge tube positioned therein ready for use; Fig. 2 is a diagrammatic view of my complete transmitter including the operating parts and portions and their connecting electric circuits; and Fig. 3 is a longitudinal sectional view of the gas discharge tube.

Similar characters of reference refer to similar parts in the views of the drawings:

The gas discharge tube 1, external electrode 2, condenser 3, resistance 4, transformer 5, rectifier tube 6, resistance 7, condenser 8, spark coil 9, contactor 10, motor 11, cylindrical parabolic reflector 12 and filter film 13 constitute the principal parts of my light signalling means.

The gas discharge tube 1 preferably contains argon and this tube is positioned in its proper relation in the cylindrical parabolic reflector 12 as shown in the drawings. Connected at its one end is the terminal of electric wire 1a and at its other end is the terminal of the electric wire 1b. These terminals are in the form of internally connected electrodes of usual form. Mounted on the middle of this gas discharge tube 1 is an external electrode 2 which connects with an elec-

2

tric wire 2a. Connecting the electric wires 1a and 1b is an electric wire 3a, in which is positioned a condenser 3. This wire 3a terminates with a ground 3b. Positioned in the wire 1a is a resistance 4 and connected with the wire 1b is a transformer 5 and electrically connected with the transformer 5 is a rectifier tube 6. The electric wire 2a from the external electrode 2 connects with the high voltage terminal of a spark coil 9. This spark coil 9 is operated by means of a contactor 10 which discharges a condenser 8 through the primary of the spark coil 9. The condenser 8 is charged from the same voltage source as the main condenser 3, but through a higher resistance 7 of about one-half megohm. This contactor 10 is operated by the motor 11. Connected across the wires 4a and 6a is an electric wire 4b. The spark coil 9 connects with the ground 3a by means of a wire 9b. Connecting with this wire 9b is the wire 8a in which the condenser 8 is mounted and the resistance 7. From this wire 8a extends a wire 10a which connects with one side of the contactor 10. The other side of the contactor connects with the spark coil 9.

It will be here noted that the light produced by the electric discharge through the tube 1 is rendered invisible to the eye by means of a light absorbing filter which absorbs the visible light and transmits the desired invisible radiation. The glass wall of the discharge tube 1, when composed of filter glass of suitable characteristics, may comprise the filter; or the tube 1 may be made of clear glass and the filter applied to the outer surface of the tube as an adherent film on the outer surface or closely related thereto. It will also be noted that the argon gas used in the gas discharge tube 1 has a powerful spectrum in the infra-red region to which the photo-electric cells of the caesium silver oxide type are most sensitive. It will also be noted that the powerful lines in the red and infra-red spectrum of argon gas exists at 6965, 7067, 7503, 8115, 8425, and 9123 angstroms. The visible light in the argon spectrum is removed by the absorption filter of the tube 1, the filter being applied as hereinbefore described. It will also be noted that the argon gas discharge tube 1 generates very little energy in the infra-red spectrum which is outside the responsive range of the photo-electric cell, this being one of its greatest advantages over the incandescent filament or electric arc in both of which a large percentage of the infra-red energy is generated at wave lengths which do not effect the photo-

electric cell, but do result in the production of useless and excessive heat. It will also be noted that the gas discharge tube, when operated as herein described, is a source of light of extremely high instantaneous intensity, but that the flashes of light produced are of very short duration of the order of 25 microseconds. The excellent high frequency response characteristic of the photo-electric cells used for receiving permits the efficient utilization of light flashes of 10 very short duration.

The operation of my means is substantially as follows:

The gas discharge tube 1 is positioned at the focus of the cylindrical parabolic reflector 12 with a focal length of substantially one and one-half inches. The aperture of the reflector is substantially twenty inches and the cylindrical axis about twenty inches. Connected across the tube terminals 1a and 1b is a high voltage condenser 3 with a capacity of about four microfarads. The condenser is charged through a 2000 ohm resistance 4 from a 1000 volt pulsating direct current source consisting of the transformer 5 and rectifier tube 6 which obtains its power from the 110 volt 60 cycle line 5a. The gas pressure in the discharge tube 1 is made such that the breakdown voltage of the tube is considerably more than 1000 volts. Therefore the condenser charges to the peak voltage supplied by the rectifier tube 6 and does not discharge through the tube until the path through the discharge tube 1 is ionized by a high voltage applied by the spark coil 9. This high voltage is applied to the external electrode 2 at the middle of the tube 1 through the wire 2a, it being noted that no internal connection is required to introduce the ionizing voltage. The spark coil 9 is operated by means of the contact maker 10 which discharges a one-quarter microfarad condenser 8 at 1000 volts through the primary of the coil 9. This condenser is charged from the same voltage source as the main condenser 3 but through a higher resistance 7 about one-half megohm. The contactor 10 is driven by the driving motor 11. The speed of the signalling is limited only by the amount of energy that may be dissipated by the negative electrode of the gas discharge tube 1 without overheating. It is therefore desirable to use a large negative electrode for this reason.

Though I have shown and described a particular construction, combination and arrangement of parts and portions, and have described certain obvious modifications, I do not wish to be limited to this particular construction, combination and arrangement, but desire to include in the scope of my invention the construction, combination and arrangement substantially as set forth in the appended claims.

The invention herein described and claimed may be used and manufactured by or for the Gov-

ernment of the United States of America for governmental purposes without the payment of any royalties thereon or therefor.

Having thus described my invention, what I claim as new and desire to secure by Letters Patent is:

A communication system employing directed beam invisible electromagnetic radiation; comprising a directable parabolic reflector having a focal region, a gaseous discharge source of said radiation positioned in said focal region for emitting a narrow beam radiation pattern and having a cathode and anode at the respective ends thereof, energy storage means externally connected between said cathode and anode of said radiation source, means continuously supplying direct current energy to said storage means at a potential below the discharge potential for the radiation source, an electrode external to said radiation source and disposed adjacent thereto adapted for initiating discharges therein, a circuit including a switch controllable at will by an operator for encoding a message in said beam, said circuit being connected from said direct current energy supply to ground, electrical coupling means in said circuit connected to said electrode and adapted for applying substantially said direct current potential to the electrode when said switch is closed, and energy storage means parallel connected across said circuit for instantaneously increasing the current flow to the electrode and for preventing sufficient re-energization of said electrode to cause further initiation of said discharge for an interval, whereby multiple initiations of radiation from a single closure of the switch are prevented.
